UNITED STATES PATENT OFFICE

POUL ARNE SCOTT IVERSEN, OF COPENHAGEN, DENMARK

PUMP

Application filed April 6, 1927, Serial No. 181,574, and in Denmark March 22, 1927.

The present invention relates to a fuel pump which is intended to deliver small quantities of a liquid under high pressure and which is particularly suited for internal combustion engines.

Such pumps work under particularly difficult conditions as they must impart to the liquid fuel a very high pressure (300 atmospheres or much more) and must at the same time deliver very small quantities (only fractions of a cubic centimetre) at each stroke, and moreover these quantities must vary finely according to the momentary output of the engine. In order to meet these latter demands all leakage of the pump must be avoided but it is very difficult to obtain this as the pump works under such very high pressure.

According to the present invention an absolute tightness is obtained by employing an auxiliary pump which acts initially to compress the fuel on the outer side of the stuffing box and the inlet valve to the main pump or pump proper, to a pressure which is only a little below the working pressure of the pump. This auxiliary pump, which is not intended to deliver the small quantities of fuel, need not be absolutely tight, but this is now easily obtained by the main pump, as the apparatus now works with a very small difference in pressure on the two sides of the stuffing box and the inlet valves.

In the accompanying drawing a sectional view, more or less diagrammatic, of one form of pumping apparatus according to the invention is shown.

The pump consists of a body 1, in the interior of which are formed two cylindrical chambers 2 and 3 for the auxiliary pump plunger 4 and the main or fuel pump plunger 6, respectively. The plunger 4 reciprocates in the chamber 2, being driven in known manner from the shaft of the engine and at the same time under control of the engine governor. The plunger 4 is packed by means of a stuffing box 5 of known construction.

The main pump plunger 6 is built in one with this plunger 4, the arrangement being such that the two plungers 4 and 6 are disposed coaxially behind each other. The main pump chamber 3 is separated from the auxil-

iary pump chamber 2 by means of a stuffing box 7 with a leather packing 8.

The auxiliary pump chamber is provided with an inlet valve 9 and a safety valve 10, which valves can be adjusted and are shown in the drawing as spring loaded balls. Behind the safety valve 10 there is bored in the pump body a passage 11 which leads into an annular chamber 12 formed in the pump body and surrounding the plunger 4. Another passage 13 connects the said chamber 12 with the inlet passage 14. From the auxiliary pump chamber 2 an inlet passage 15 equipped with an adjustable inlet valve 16 leads to the main pump chamber 3; and from the latter chamber the outlet passage 17, controlled by the valve 18, leads to the injector or to the engine cylinder.

When the auxiliary plunger 4 moves outward or downward, the suction thereby created in the auxiliary pump chamber 2 will open the inlet valve 9 and fuel will be drawn through passage 14 into said chamber, so that the pressure in the chamber during this period will be kept the same as that in the fuel tank or container (not shown) from which the fuel is supplied to passage 14, i. e., approximately atmospheric pressure. The annular chamber 12 is not uncovered by plunger 4 during its downward movement but, on the contrary, is kept constantly closed thereby. The main plunger 6, being attached to plunger 4, moves downward simultaneously with the same and thus creates suction in the main pump chamber 3, whereby valve 16 will be caused to open and fuel will flow from chamber 2 through passage 15 into chamber 3. Hence it will be apparent that at the end of the downward or suction stroke, both chambers 2 and 3 will be filled with fuel.

The compression or upward stroke then commences, and during this stroke plunger 4 will compress the fuel in chamber 2 to an extent determined by the adjustment of the safety valve 10, so that during the entire compression stroke a pressure is maintained in said chamber which, according to the invention, is only a trifle lower than the working pressure in the main pump chamber 3. When the pressure of the fuel becomes great enough

to open valve 10, which takes place gradually as the plunger 4 continues its stroke, fuel will be forced out through said valve and then through passage 11 to the annular chamber 12, whence it returns through passage 13 to the inlet passage 14.

The main plunger 6 moves upward, of course, with the auxiliary plunger 4 during the compression stroke of the latter and, in consequence, creates the desired pressure in chamber 3. This pressure, however, is somewhat higher than that determined in chamber 2 by the safety valve 10, so that the valve 16 will be kept closed; but valve 18, on the other hand, will be opened and the fuel compressed to high pressure in chamber 3 will be discharged therefrom through the delivery passage 17 to the internal combustion engine.

It will thus be seen that the auxiliary plunger 4 sucks in fuel at atmospheric pressure and itself produces the entire increase of pressure desired; whereas the main plunger 6 serves merely to keep the pressure on the outer side of packing 8 and valve 16, during the compression stroke of plunger 4, at nearly the same height as the working pressure of the latter, thus insuring complete tightness of these parts.

During the delivery period no oil will be able to pass out through the stuffing box 7, 8 or through the valve 16 from the main pump chamber 3, because on the outer side of these parts there will be a pressure which is only a little lower than the working pressure and it will be easy to secure a perfect tightness for such small differences in pressure.

The auxiliary pump plunger need not be built in unit form with the main or fuel pump plunger. It is only necessary that it maintain a similar pressure in a chamber corresponding to the auxiliary pump chamber 2 shown here, so that the difference in pressure on the two sides of the stuffing box 7 and the valve 16 will be small during the delivery period.

What I claim as new is:

1. Pumping apparatus, comprising a main pump chamber and an auxiliary pump chamber, a reciprocating plunger in each chamber, and a supply passage leading from the auxiliary pump chamber to the main pump chamber; both plungers making their corresponding strokes in unison, so that fluid will be drawn into the auxiliary pump chamber and supplied therefrom through said passage to the main pump chamber during the suction stroke of the plungers, and will be discharged in small quantity under high pressure from said main pump chamber and simultaneously compressed in said auxiliary chamber to a pressure which is only slightly below the working pressure in the main pump chamber during the compression stroke of the plungers.

2. Pumping apparatus, according to claim

1, in which the two plungers are directly connected together to move as a unit in the same direction.

3. Pumping apparatus, according to claim 1, in which an adjustable safety valve is associated with the auxiliary pump chamber to control the pressure therein. 70

4. Pumping apparatus, according to claim 1, in which an adjustable safety valve is associated with the auxiliary pump chamber to control the pressure therein; and in which the two plungers are directly connected together to move as a unit in the same direction. 75

5. Pumping apparatus, comprising a body formed with two alining chambers; an auxiliary plunger working in one chamber and a main plunger working in the other chamber; an inlet valve for the auxiliary chamber; a supply passage leading from the latter chamber to the main chamber; and an outlet passage leading from said main chamber, both passages being equipped with normally closed valves; said plungers making their corresponding strokes in unison and in the same direction, so that fluid will be drawn into the auxiliary chamber and thence through the supply passage into the main chamber so as to fill both chambers during the suction stroke of the plungers, and will be discharged in small quantity under high pressure from said main chamber through the outlet passage and simultaneously compressed in said auxiliary chamber to a pressure which is only slightly below the working pressure in the main chamber during the compression stroke of the plungers. 80 85 90 95

6. Single-stage pumping apparatus, comprising a main pump chamber; an inlet valve therefor; a stuffing box for said chamber; a main plunger passing through the stuffing box and operating in said chamber for discharging small quantities of fluid under high pressure; an auxiliary pump chamber on the outer side of said stuffing box and said inlet valve; an auxiliary plunger for compressing the fluid in the auxiliary chamber to a pressure only slightly below the working pressure in the main chamber; and an adjustable safety valve associated with the auxiliary chamber to control the pressure therein, said auxiliary plunger making its pressure stroke during the pressure period of the main plunger so that the safety valve can open in safety during such period. 100 105 110 115

7. Single-stage pumping apparatus, comprising a main pump chamber; an inlet valve therefor; a stuffing box for said chamber; a main plunger passing through the stuffing box and operating in said chamber for discharging small quantities of fluid under high pressure; an auxiliary pump chamber on the outer side of said stuffing box and said inlet valve; and an auxiliary plunger for compressing the fluid in the auxiliary chamber to a pressure which is only slightly below the 120 125 130

working pressure in the main chamber, the main and auxiliary plungers being rigidly connected together to form a unit.

8. Single-stage pumping apparatus, comprising a main pump chamber; an inlet valve therefor; a stuffing box for said chamber; a main plunger passing through the stuffing box and operating in said chamber for discharging small quantities of fluid under high pressure; an auxiliary pump chamber on the outer side of said stuffing box and said inlet valve; an auxiliary plunger for compressing the fluid in the auxiliary chamber to a pressure which is only slightly below the working pressure in the main chamber; and an adjustable safety valve associated with the auxiliary chamber to control the pressure therein; an inlet passage for the fluid and an overflow passage being provided, the overflow passage leading from the safety valve to the inlet passage.

In testimony whereof I affix my signature.
POUL ARNE SCOTT IVERSEN.
